UNITED STATES PATENT OFFICE.

HERBERT R. KEITHLEY, OF BUFFALO, NEW YORK.

CAR-TRUCK.

SPECIFICATION forming part of Letters Patent No. 700,425, dated May 20, 1902.

Application filed November 27, 1901. Serial No. 83,857. (No model.)

To all whom it may concern:

Be it known that I, HERBERT R. KEITHLEY, a citizen of the United States, residing at Buffalo, in the county of Erie and State of New York, have invented new and useful Improvements in Car-Trucks, of which the following is a specification.

This invention relates more particularly to the frame construction of diamond car-trucks.

10 My invention has for its object to reduce the number of parts of the truck-frame to a minimum and to so construct the connected frame members as to increase their riveting area or surfaces, thereby correspondingly increasing 15 the strength and stiffness of the truck-frame.

In the accompanying drawings, Figure 1 is a side elevation of a car-truck embodying my invention. Fig. 2 is an end view of the same, showing one half of the truck-frame in elevation and the other half in section, the plane of the sectional portion being in line 2 2, Fig. 1.

Like letters of reference refer to like parts in both figures.

25 A is the upper arch-bar, and B the lower arch-bar, of each side frame of the truck. The upper arch-bar is preferably constructed of pressed steel and composed of a longitudinal top plate a , two vertical webs a' , extending downwardly from opposite edges of said top plate, and horizontal flanges a'' , projecting outwardly from the lower edges of said webs, as most clearly shown in Fig. 2. These webs and flanges also preferably extend 30 around the ends of the upper arch-bar, as shown at a^3 , Fig. 2.

In the construction shown in the drawings the crown on the central portion of the upper arch-bar is deeper than its end portions a^4 , 40 which latter are horizontal, and the portions thereof between the deep middle portion and the shallow end portions gradually increase in depth toward the middle portion, as shown in Fig. 1.

45 The lower inverted arch-bar B may consist of an ordinary solid bar, and its horizontal end portions are secured to the under side of the corresponding portions of the upper arch-bar by vertical rivets, which pass through the 50 flanges a'' of the upper bar and the end portions of the lower arch-bar.

C represents the usual axle-boxes.

D is the pedestal tie-bar, and E vertical tie-bolts passing through the contiguous ends of the two arch-bars and the pedestal tie-bar. 55

F is the transom, which is preferably constructed of a single blank of pressed steel and composed of a horizontal bottom plate f and parallel webs f' , extending upwardly from opposite edges of said plate and each provided 60 at its upper edge with an outwardly-extending flange f'' . The webs f' are preferably connected together at the ends of the transom by tie-plates g , which connect both flanges of the transom and both flanges of the upper 65 arch-bar, these plates being secured to said flanges by bolts or rivets h . The end portions of the transom are arranged between the upper and lower arch-bars of the side frames and are rigidly secured to the lower arch-bars 70

by bolts or rivets i , which pass through said bars and the bottom plate f of the transom, and to the upper arch-bars by bolts or rivets i' , which pass through the tie-plates g of the transom and the lateral flanges a^3 of the upper arch-bar. 75

In diamond car-trucks of the ordinary construction the horizontal end portions of the upper and lower arch-bars are connected together at each end by but two vertical bolts, 80 which receive all of the shearing strains. Under heavy loads these bolts gradually become bent from such shearing strains, causing a permanent "set" or downward deflection of the side frames. In my improved truck-frame the large riveting area afforded by the flanges of the upper arch-bar permits the use of a sufficient number of rivets or bolts to effectually resist such shearing strains, thereby preventing deflection of the side frames. 85

The peculiar construction of the transom affords a similar large riveting area for connection to the side frames, and by forming the same in a single piece its strength and stiffness are increased and the number of 90 parts is reduced.

J is the bolster, which is supported on the transom by springs K, arranged within the transom at the ends of the bolster and resting upon plates l , which in turn rest upon the 100 bottom plate of the transom. The bolster is composed of parallel side webs j , which have

outwardly-extending bottom flanges j' and inwardly-extending top flanges j^2 , a bottom tie-plate, which is arranged beneath and secured to the bottom flanges j' by rivets, and 5 a top tie-plate, which connects the side webs and is secured to the inwardly-extending top flanges by rivets. The bolster is preferably provided at each end with a pair of bent guide-plates j^3 , which are riveted to the side webs 10 above the outwardly-extending bottom flanges. These guide-plates bear on the inner sides of the transom-webs and guide the bolster in its movement therein.

I claim as my invention—

15 1. A side frame for diamond car-trucks having a lower arch-bar, and an upper arch-bar formed from a single piece of metal, and composed of a longitudinal top plate and vertical webs extending downwardly from the edges 20 of said plate and provided at their lower edges with outwardly-extending flanges which are riveted to the end portions of the lower arch-bar, substantially as set forth.

25 2. A side frame for diamond car-trucks having a lower arch-bar, and an upper arch-bar formed from a single piece of metal, and composed of a longitudinal top plate and vertical webs extending downwardly from the edges of said plate and provided at their lower edges 30 with outwardly-extending flanges which extend around the ends of the bar and which are riveted to the end portions of the lower arch-bar, substantially as set forth.

35 3. A side frame for diamond car-trucks having a lower arch-bar, and an upper arch-bar formed from a single piece of metal and having its middle portion constructed of greater depth than its end portions, and composed of a longitudinal top plate and vertical webs ex- 40 tending downwardly from the edges of said

plate and provided at their lower edges with outwardly-extending flanges which are riveted to the end portions of the lower arch-bar, substantially as set forth.

4. The combination with the side frames of 45 a car-truck each having an upper arch-bar or compression member formed from a single piece of metal and composed of a longitudinal top plate and vertical webs extending downwardly from the edges of said plate and provided at their lower edges with outwardly-extending flanges, of a transom composed of a bottom plate, parallel webs extending upwardly from the edges of said plate and formed integral therewith and provided at their upper edges with outwardly-extending flanges, 50 substantially as set forth.

5. The combination with the side frames of a car-truck each having an upper arch-bar or compression member formed from a single 55 piece of metal and composed of a longitudinal top plate and vertical webs extending downwardly from the edges of said plate and provided at their lower edges with outwardly-extending flanges, of a transom composed of a bottom plate, parallel webs extending upwardly from the edges of said plate and formed integral therewith and provided at their upper edges with outwardly-extending flanges, 60 substantially as set forth.

65 70 2. A side frame for diamond car-trucks having a lower arch-bar, and an upper arch-bar formed from a single piece of metal and composed of a longitudinal top plate and vertical webs extending downwardly from the edges of said plate and provided at their lower edges with outwardly-extending flanges, of a transom composed of a bottom plate, parallel webs extending upwardly from the edges of said plate and formed integral therewith and provided at their upper edges with outwardly-extending flanges, and plates which are bolted or riveted to the flanges of the transom-webs and to the flanges of said upper arch-bars, substantially as set forth.

Witness my hand this 18th day of November, 1901.

HERBERT R. KEITHLEY.
